(57) **CLAIM**

The ornamental design for an electronic animal call, as shown and described.

DESCRIPTION

FIG. 1 is an isometric top, left and front side view of an electronic animal call, showing our new design;

FIG. 2 is an isometric top, right and rear side view thereof;

FIG. 3 is a front side view thereof;

FIG. 4 is a rear side view thereof;

FIG. 5 is a top side view thereof;

FIG. 6 is a bottom side view thereof;

FIG. 7 is a right side view thereof; and,

FIG. 8 is a left side view thereof.

The portions of the article in broken lines are for illustrative purposes only and form no part of the claimed design.

1 Claim, 8 Drawing Sheets
